UNITED STATES PATENT OFFICE.

WESLEY HANKINSON AND JACOB J. KNEBEL, OF KANSAS CITY, MISSOURI.

WRIST-WATCH STRAP.

Application filed August 9, 1926. Serial No. 128,189.

Our invention relates to improvements in wrist watch straps, and our object is to provide a neat and attractive strap of this character having its margins decorated with ornamental lacings as will hereinafter appear, reference being had to the accompanying drawing, in which:

Fig. 1 shows the strap attached to a wrist watch.

10 Fig. 2 is a detail edge view showing the two sections of the finished strap.

Fig. 3 is a plan view of the parts disclosed by Fig. 2.

15 Fig. 4 is a detail plan view of the two sections of the strap without the lacings.

Referring in detail to the different parts, 2 designates one section and 4 the companion section of the strap. The section 2 is provided at its ends with loops 6 and 8, the 20 former of which is equipped with a buckle 10 while the loop 8 is adapted to be attached to one side of a wrist watch A. The strap section 2 is provided at its ends with laterally projecting shoulders 12 and 14 constituting important features of the invention. Said strap section 2 is also provided adjacent to the shoulders 12 with an enlargement 16 which has a keeper 18 mounted thereon.

25 The companion strap section 4 has a series of holes 20 any of which are adapted to receive the tongue of the buckle 10 when the two sections 2 and 4 are secured around the wrist to hold the watch A in position. The section 4 is provided at one end with a loop 22 and laterally projecting shoulders 24, which latter like the shoulders 12 and 14 constitute important features of the invention. The loop 22 forms convenient means whereby the strap section 4 can be attached 30 to the watch A at a point diametrically opposite the strap section 2.

35 26 designates lacings which are sewed or otherwise suitably applied to the two longitudinal margins of the strap section 2. The lacings 26 consist of leather or other suitable material and extend from the shoulders 12 to the shoulders 14. Said lacings 26 overlap the margins of the strap 2 in order to come flush or approximately flush with the sides 28 and 30, respectively, of said shoulders. The lacings 26 also secure the ends of the keeper 18 to the enlargement 16.

40 The strap section 4 is provided with lacings 32, which extends from the shoulders 24 along the longitudinal margins and around one end of said section 4, as best

shown by Figs. 1 and 3. The lacing 32 is preferably applied in the same manner as the lacings 26 and overlaps the margins of the section 4 in order to come flush or approximately flush with the sides 34 of the shoulders 24.

45 By providing the strap sections 2 and 4 with lacings 26 and 32, respectively, it is apparent that the margins of said strap sections are not only protected from wear and prevented from curling up or otherwise getting out of shape, but said lacings lend an ornamental and distinctive appearance to said strap sections. It is also apparent that the 50 laterally projecting shoulders 12, 14 and 24 protect the ends of the respective lacings and by coming flush or approximately flush with the projecting portions of said lacings enhance the appearance of the finished article.

55 While we have shown and described the preferred form of our invention, we reserve all rights to such changes and modifications thereof as properly fall within the spirit and scope of the invention as claimed.

Having thus described our invention, what we claim and desire to secure by Letters Patent, is:

1. A strap having an enlarged portion, a keeper mounted upon said enlarged portion, 60 and lacings secured to said strap and holding the keeper in place upon said enlarged portion.

2. A strap consisting of two sections, a buckle secured to one of said sections, lacings secured to said sections and projecting over certain narrow margins thereof, and shoulders on certain narrow margins of said strap sections which are approximately flush with the projecting portions of the respective lacings.

3. A strap consisting of two sections each having a loop at one end for attachment to a wrist watch, lacings secured to and projecting over certain margins of said sections, and marginal shoulders on said sections having an edge approximately flush with the projecting portions of said lacings.

4. A strap provided at its narrow margins with laterally projecting shoulders, and lacings secured to the strap between said shoulders and projecting over the adjacent narrow margins of said strap.

In testimony whereof we affix our signatures.

WESLEY HANKINSON.
JACOB J. KNEBEL.
